UNITED STATES PATENT OFFICE.

ROBERT COLLEN, OF LONDON, ENGLAND.

MACHINERY FOR MANUFACTURING CASKS OR BARRELS.

SPECIFICATION forming part of Letters Patent No. 606,516, dated June 28, 1898.

Application filed December 24, 1897. Serial No. 663,366. (No model.) Patented in England July 28, 1896, No. 16,670.

To all whom it may concern:

Be it known that I, ROBERT COLLEN, engineer, a subject of the Queen of Great Britain and Ireland, residing at 30 Pigott street, 5 Limehouse, in the city of London, England, have invented certain Improvements in Machinery for Manufacturing Casks or Barrels, (for which I have, in conjunction with George Mills, deceased, late of Castor street, Poplar, 10 in the said city of London, obtained a patent in Great Britain, No. 16,670, dated July 28, 1896,) of which the following is a specification.

This invention has for its object to provide a machine, herein for convenience termed a 15 "crozing-machine," for use in the manufacture of casks or barrels and which at a single operation effects the crozing, chiming, and "jiggering" operations—that is to say, forms the grooves or crozes into which the heads are 20 fitted, chamfers or rounds off the ends of the staves, and levels the inner faces of the staves adjacent to the crozes.

The apparatus herein described is applicable for use in the manufacture of vessels or 25 bodies other than those ordinarily known as "casks"—for example, tubs, vats, tubes, or the like—and I wish it to be understood that whenever in this specification and claims the context admits of such an interpretation 30 the word "cask" or "casks" is intended to include all such structures.

The invention will be best understood by reference to the accompanying drawings, in which—

35 Figure 1 is a front elevation shown partly in section, and Fig. 2 a side elevation, of the improved crozing-machine. Fig. 3 is a vertical section on the line 3 3 of Fig. 2, but drawn to a scale larger than that to which Fig. 2 is 40 drawn. Fig. 4 is an under side view of the cutter-head shown in Figs. 1, 2, and 3, drawn to a scale the same as that to which Fig. 3 is drawn. Figs. 5 and 6 are respectively an under side view and an elevation of the table. 45 Fig. 7 is a plan of the lower cone of the crozing-machine; and Figs. 8 and 9 are views, partly in elevation and partly in section, of upper and lower cone-rings, respectively, applicable to the crozing-machine, as hereinafter 50 described.

Like letters of reference indicate like parts

throughout the several figures of the drawings.

The crozing-machine, as shown in Figs. 1 and 2, comprises a stationary frame O, in the upper part of which is mounted a revolving vertical shaft P, and at the lower part is provided a circular frame or cone Q, hereinafter termed the "lower" cone, capable of being moved upward on guide-bars o by a hydraulic ram Q', of which only a part is shown. If desired, the lower cone may be raised by power other than hydraulic. Another circular frame or cone Q², hereinafter termed the "upper" cone, is adjustably secured on the guide-bars o, which are screw-threaded for a portion of their length—for example, by nuts o' and clamping-screws o², of which latter only one is shown, though there may be one such screw for each of the two front bars or for each of the three bars o. The upper cone Q² is generally secured a little below the level of the cutter-head P', which is secured to the lower end of the revolving shaft P. Within the lower cone Q is fitted a table q, Figs. 1, 2, 5, 6, which when the said lower cone is in its lowermost position, as shown in full lines in Figs. 1 and 2, extends above the level of the said cone, the legs q' of the table then resting on the base-plate O' or other suitable surface. When the lower cone Q is raised, the table q is received in the interior of the said cone, as indicated in dot-and-dash lines in Fig. 1. The last-described arrangement provides a readier means of getting the cask or barrel R, Fig. 1, into position than would be the case if the cask or barrel had to be lifted into and out of the lower cone Q at the beginning and termination of the operations.

The cutter-head P' carries tools or cutters p p' (the former forked, as shown, and the latter having a straight chisel edge) for forming the croze or groove for receiving the cask-head, preferably two diametrically opposite tools p² for effecting the chiming operation, and a tool p³ for effecting the jiggering operation, all of which operations are carried out simultaneously. The tools or cutters p, p', p², and p³ are detachably secured to tool-carriers p⁴, engaging with screw-threaded shafts p⁵, all connected by bevel-gearing p⁶ to a vertical shaft S, hereinafter termed the "inner"

shaft, extending axially through the cutter-shaft P, by which arrangement all the tools while being rotated by the said cutter-shaft may be simultaneously moved radially outward for feeding the tools up to their work or radially inward for moving them away from the work at the completion of the cutting operations.

- The cutter-shaft P is rotated from the main 10 or first driven shaft P² by bevel or other gearing P³, and near the upper end of the inner shaft S is loosely mounted a pulley s, rotated by a belt s', driven from the main shaft P², and on a conveniently left-handed screw-threaded collar S', Fig. 3, at a lower part of the said inner shaft is secured a hand-wheel S², which is preferably formed with a wooden rim, as indicated in Fig. 3, or is otherwise made as light as practicable, so that it may 20 not acquire appreciable momentum when rotated or present appreciable inertia when about to be rotated, by which means the jamming of the screw-threaded shafts p⁵ in their nuts is prevented.
- 25 On the upper end of the inner shaft S is secured a conical friction-cup S³, having its mouth or open end presented downward and adapted to receive the upper and conical end of the boss of the above-mentioned pulley s.
- 30 The hand-wheel S² is provided with an upwardly-extending conical friction-cup S⁴, adapted to receive the lower and taper end of a non-rotating split sleeve S⁵, whose two parts s⁵ are connected together near their upper ends by blade-springs s², which when the sleeve S⁵ is clear of the cup s⁴ hold the two parts s⁵ out of contact with the inner shaft S and which yield sufficiently to admit of the two said sleeve parts gripping the inner shaft 40 when they are forced downward into the friction-cup S⁴. The split sleeve S⁵, which, as it were, constitutes a brake for the shaft S, is pivoted in or to a fork S⁶, which may be raised and lowered by means of a hand-lever s³.
- 45 The pulley s rotates in the same direction as but at a higher speed than the cutter-shaft P, so that when the fork S⁶ is raised, and the boss of the pulley s is consequently forced into the cup S³, the inner shaft S will outrun the 50 cutter-shaft P and through the bevel-gearing p⁶ and screw-threaded shafts p⁵ cause the tools or cutters p p' p² p³ to be moved inward. When the fork S⁶ is lowered, and the split sleeve S⁵ is consequently forced into the 55 friction-cup S⁴, the inner shaft S is retarded or prevented from rotating, so that during the further rotation of the cutter-head P' (the screw-threaded shafts p⁵ being carried around bodily with the said cutter-head) the tools or 60 cutters p p' p² p³ are moved outward. As the engagement of the sleeve S⁵ with the cup S⁴ and of the pulley s with the cup S³ is frictional, these parts slip over each other when the limits of the inward and outward movements of the tools or cutters are reached, even 65 though the lever s³ be retained in either of

its two operative positions. When the lever S³ is free, both of the before-described friction devices are disengaged and the inner shaft rotates at the same speed as the cutter-shaft, so that the tools or cutters rotate with the cutter-head without being moved radially therein.

To reduce friction, I prefer to provide ball-bearings T between the upper end of the cutter-shaft P and the collar S' and between the upper end of the split sleeve S⁵ and the pulley s.

When the last-described machine is at work, the cutter-head P' is kept constantly rotating, and the previously-trussed cask or barrel R to be operated upon has first introduced into it an india-rubber diaphragm, which fits tightly into its interior, for the purpose of preventing the shavings from falling through the said cask or barrel onto the lower cone Q or parts adjacent thereto. The cask is then placed on the table q and the lower cone Q raised by the ram Q', which forces the upper end of the cask into the upper cone Q² and properly centers the cask and retains it in position. The before-mentioned split sleeve S⁵ is then depressed, so as to retard or prevent the rotation of the inner shaft S, and thereby, as previously described, cause the cutters to move outward to effect the cutting operations, and afterward the split sleeve is raised so as to cause the cutters to be moved inward, the relative speeds of rotation of the cutter-shaft P and pulley s being preferably such that the cutters are caused to move slowly outward and quicker inward. The lower cone Q is then allowed or caused to descend, and the cask or barrel R is then successively removed from the table q and emptied of the shavings, inverted, and replaced on the table, after which the before-described operation is repeated.

When it is desired to employ the crozing-machine for casks of a smaller size than that which the before-described cones are adapted to receive, other cones or rings U U', Figs. 8 and 9, of smaller diameter may be fitted in those first described. The removable upper cone or ring U is provided with an annular shoulder u, with which bolts or screws in the upper cone Q² may engage to retain it in position therein, and the removable lower cone or ring U' is adapted to remain in position merely by its own weight and to receive a table smaller than that fitting directly into the lower cone Q.

To limit the extent to which the tools are to cut into the cask or barrel, readily-removable stops V, Fig. 3, of varying thicknesses may be provided in the guides or slots P⁴, in which the said tools or their holders move radially outward and inward in the cutter-head P'. The tools may be moved outward and inward for adjustment when the machine is at rest by rotating the hand-wheel S².

Having now particularly described and as-

certained the nature of this invention and in what manner the same is to be performed, I declare that what I claim is—

1. In a crozing-machine, the combination of a revolving head carrying tools or cutters for effecting the crozing, chiming and jigging operations, automatic mechanism capable of giving said cutters radial movement either inward or outward with relation to the cutter-head, and means under the control of the operator and capable of causing said mechanism to operate to produce either of said radial movements of the cutters, substantially as described.
- 15 2. In a crozing-machine, a revolving cutter-head, crozing, chiming and jigging tools carried by the cutter-head and capable of radial movement inward and outward relative thereto, means capable of giving the tools movement in either direction and means whereby the direction of movement of said tools may be controlled, substantially as described.
- 25 3. In a crozing-machine, a cutter-head, tools carried by said cutter-head and capable of radial movement relative thereto, a shaft supporting the cutter-head, a second shaft operatively connected to the tools on said head, and means imparting differential revolutions to the two shafts, and means capable

of altering the rate of speed of one shaft with relation to the other whereby the radial movements of the tools are effected, substantially as described.

4. In a crozing-machine, a revolving cutter-shaft, cutting-tools supported thereby, an independently-rotatable shaft effecting the movement of the cutting-tools to and from their work, means imparting differential speed revolutions to the two shafts, means capable of varying the rate of speed of one of the shafts substantially as described.

5. In a crozing-machine, a revolving cutter-shaft, cutting-tools supported thereby, a second shaft concentric with the cutter-shaft and controlling the movement of the tools to and from their work, means causing one shaft to revolve faster than the other, and means for altering the rate of speed of one of the shafts to make it rotate either faster or slower than the other shaft, substantially as described.

In testimony whereof I have signed my name to this specification in the presence of two subscribing witnesses.

R. COLLEN.
